APPARATUS FOR HANDLING STRIP MATERIAL

Adolph Potdevin, Garden City, N. Y., assignor to
 Potdevin Machine Company, Brooklyn, N. Y.,
 a corporation of New York

Application January 8, 1932, Serial No. 585,519

8 Claims. (Cl. 271—2.2)

This invention relates to an improvement in machines for handling flexible sheet material and provides an apparatus which is particularly well suited for the handling of cellophane and similar material.

One of the objects of my invention is the provision of a construction whereby the usual slack is produced in the material prior to the cutting-off operation, means being provided, however, whereby tension is maintained in the material between the point of cut-off and the feed rollers thereby preventing wrinkling or creasing of the material. This is particularly advantageous when handling cellophane or similar material inasmuch as creases or wrinkles therein cause the material to crack and shatter unfitting the material for use.

In the drawing:

Fig. 1 is a sectional elevational view of an embodiment of my invention;

Fig. 2 is a view with the parts in different position; and

Fig. 3 is a plan view.

Referring to the drawing in detail, 1 and 2 designate, respectively, the upper and lower feed rollers of a bag making machine, these rollers advancing the material 3 to a pair of pinch rolls 4 and 5 and from thence to advancing rollers 6 and 7.

Intermediate the feed rollers and pinch rolls I provide cutting-off mechanism comprising the plates 8 and 9 and striker bar 10. The construction so far mentioned is well known.

When handling cellophane or similar material I prefer to heat the plate 9 slightly by the application of a heater 11 thereto which may be an electric hot plate.

The pinch rolls 4 and 5 travel at a lower peripheral speed than the feed rollers 1 and 2 and hence when the active portion 12 of the pinch roll 4 moves to operative position the advance of the material 3 is retarded to produce a slack in the material which is desired for the cutting-off operation.

The present invention has for one of its objects means whereby this slack will be confined to the space between the striker bar 10 and the pinch rolls 4 and 5 so that at no time will there be slack material between the striker bar 10 and the feed rollers 1 and 2. This is of advantage with any material but is particularly advantageous when working with cellophane as creases or wrinkles in cellophane cause the same to crack and shatter and unfit it for use.

In this connection I provide a rod 13 intermediate the striker bar 10 and the pinch rolls. This

rod is fixed and the material 3 as it passes to the pinch rolls passes over the top of this bar or rod and is supported thereby.

At the rear of the pinch rolls I provide a shaft 14 adapted to be rocked in the frame of the machine, this shaft carrying a pair of arms 15 which are curved beneath the lower pinch roll 5 and carry a flat plate 16 at their free ends adjacent the rod or bar 13. The shaft 14 is additionally equipped with an arm 17 provided at its free end with a roller or cam follower 18 adapted to engage a cam 19 on the shaft for the lower pinch roll 5.

Overlying the plate 16 is an air nozzle 20 receiving air under pressure from any suitable source.

In operation the material 3 is advanced by the feed rollers 1 and 2 past the cut-off station, over the rod or bar 13, to and across the plate 16, pinch rolls 4 and 5 and to the advancing rollers 6 and 7. It will be appreciated by those familiar with this art that the pinch rolls 4 and 5 travel at a lower peripheral speed than the feed rollers, and also that they are timed so that until a predetermined length of material has been advanced, these two rolls will not pinch the paper. At the proper time, however, these two rolls engage or pinch the advancing strip and inasmuch as the peripheral speed of these rolls is lower than that of the feed rollers a slack will be created in the material 3 by the continued forward feed thereof. The air supply to nozzle 20 is on while the machine is operating, and the cam 19 is so shaped and so timed that as the slack in the material accumulates the plate 16 moves downwardly. As the air blast is on during this period the slack portion of the material will be driven downwardly to maintain tension in the material from the rod or bar 13 back to the feed rollers 1 and 2, to prevent wrinkling or creasing of that portion of the material. The force of the air blast it will be understood is sufficient to maintain tension in the material during the cutting-off operation also.

From the foregoing, therefore, it will be seen that I have provided an apparatus for handling flexible strip material in which the advancing strip is intermittently cut off or severed into lengths, means being provided for creating a slack in the material for facilitating the cutting-off operation, means being provided to maintain tension in the advancing material between the cut-off station and the feed roller to preclude creasing or wrinkling of the material.

What I claim is:—

1. In apparatus of the class described, the combination of feed rollers for continuously advancing a flexible web or strip, pinch rolls in the path of the advancing strip having a peripheral speed lower than that of the feed rollers to produce a slack in the material, and means to apply an air blast to one face of the material during the slack-forming operation. 5
10. 2. In apparatus of the class described, the combination of feed rollers for continuously advancing a flexible web or strip, pinch rolls in the path of the advancing strip and cooperating with the feed rollers to produce a slack in the advancing material, a plate beneath the advancing material 10 for supporting the slack, and means for applying an air blast to the upper face of the material during the slack-forming operation. 15
15. 3. In apparatus of the class described, the combination of feed rollers for continuously advancing a flexible strip or web, pinch rolls in the path of the advancing material, the pinch rolls and feed rollers traveling at different peripheral speeds to produce a slack in the web, a pivotally 20 mounted plate between the feed rollers and pinch rolls for supporting the material during its passage to the pinch rolls, means for applying an air blast to the other face of the material during the slack-forming period, and means for pivoting said plate in a direction away from the web during the slack-forming period. 25
20. 4. In apparatus of the class described continuously operating web advancing means, retarding means in the path of the advancing web or strip 30 for producing a slack in the web or strip, a plate beneath the web for temporarily supporting the slack and means to apply an air blast to the upper face of the material immediately above said plate during the slack-forming operation. 35
30. 5. In apparatus of the class described, the combination of web or strip advancing means, retarding means in the path of the advancing web or 40
- strip for producing a slack in the advancing material, a plate beneath the web for temporarily supporting the slack, and means to apply an air blast to the upper face of the advancing material during the slack-forming operation. 5
6. In apparatus of the class described, the combination of feed rollers for continuously advancing a flexible web or strip, pinch rolls in the path of the advancing strip and cooperating with the feed rollers to produce a slack in the advancing material, a plate intermediate the pinch rolls and the feed rollers lying beneath the advancing material for supporting the slack, and means for applying an air blast to the upper face of the material during the slack forming operation. 10
7. In apparatus of the class described, the combination of feed rollers for continuously advancing a flexible web or strip, pinch rolls in the path of the advancing strip and cooperating with the feed rollers to produce a slack in the advancing material, a plate beneath the advancing material disposed intermediate the feed rollers and pinch rolls for supporting the slack, and means for applying an air blast to the upper face of the material immediately above said plate during the slack forming operation. 15
8. In apparatus of the class described, the combination of feed rollers for continuously advancing a flexible strip or web, pinch rolls in the path of the advancing material, the pinch rolls and feed rollers traveling at different peripheral speeds to produce a slack in the web, a pivotally mounted plate between the feed rollers and pinch rolls disposed beneath the material for supporting the material during its passage to the pinch rolls, means for applying an air blast to the other face of the material abreast of said plate during the slack forming period and means for pivoting said plate in a direction away from the web during the slack forming period. 20
